US00D777147S

(12) United States Design Patent (10) Patent No.: US D777,147 S
Cheng et al. (45) Date of Patent: * Jan. 24, 2017

(54) JACKET FOR A PORTABLE SPEAKER

(71) Applicant: Fugoo Corporation, Irvine, CA (US)

(72) Inventors: Howard Shi-How Cheng, Irvine, CA (US); Alejandro Garfio, West Covina, CA (US); Ho Koon Yau, Yorba Linda, CA (US); Kit Mok, Lakewood, CA (US)

(73) Assignee: FUGOO CORPORATION, Irvine, CA (US)

() Term: 15 Years

(21) Appl. No.: 29/536,255

(22) Filed: Aug. 14, 2015

(57) CLAIM

The ornamental design for a jacket for a portable speaker, as shown and described.

DESCRIPTION

FIG. 1 is a top, front and side perspective view of a jacket for a portable speaker embodying my new design.

FIG. 2 is a bottom, back and side perspective view thereof.

FIG. 3 is a front view thereof.

FIG. 4 is a back view thereof.

FIG. 5 is a top view thereof.

FIG. 6 is a bottom view thereof.

FIG. 7 is a first side view thereof.

FIG. 8 is a second side view thereof; and,

FIG. 9 is a top, front and side perspective view thereof, shown in environmental use.

Broken lines are used to illustrate features of the jacket for a portable speaker which form no part of the claimed design. In FIG. 9, the jacket is shown surrounding a portable speaker shown to represent environment which forms no part of the claimed design. The dot dash line represents a boundary line and forms no part of the claimed design.

1 Claim, 8 Drawing Sheets
